UNITED STATES PATENT OFFICE

170,421

WHEEL COVER OR SIMILAR ARTICLE

George Albert Lyon, Detroit, Mich.

Application May 18, 1953, Serial No. 25,044

Term of patent 14 years

(Cl. D14—30)

To all whom it may concern:

Be it known that I, George Albert Lyon, a citizen of the United States, and a resident of the city of Detroit, in the county of Wayne and State of Michigan, have invented a new, original, and ornamental Design for a Wheel Cover or Similar Article, of which the following is a specification, reference being had to the accompanying drawing forming a part thereof.

On the drawing:

Fig. 1 is a side elevational view of a wheel cover or similar article embodying my new design.

Fig. 2 is a profile view showing the cross sectional contour of the cover of Fig. 1; and

Fig. 3 is a fragmentary side perspective view of the cover.

The conventional tire and wheel assembly disclosed in dotted lines are shown only for the purpose of illustration.

I claim:

The ornamental design for wheel cover or similar article, substantially as shown and described.

GEORGE ALBERT LYON.
